(57) **CLAIM**

The ornamental design for an extension bracket for insecticide spraying, as shown and described.

DESCRIPTION

FIG. 1 is a perspective view of an extension bracket for insecticide spraying showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a perspective view of the in use state;

FIG. 10 is an enlarged view of portion of FIG. 1; and,

FIG. 11 is an enlarged view of portion of FIG. 2.

The broken line showing of the extension bracket for insecticide spraying is for the purpose of illustrating article and forms no part of the claimed design.

1 Claim, 11 Drawing Sheets
